US0D1002573S

(12) **United States Design Patent** (10) **Patent No.:** **US D1,002,573 S**
(45) **Date of Patent:** **** Oct. 24, 2023**

(54) **WIRELESS SPEAKER**

(71) Applicant: **Shenzhen Zhiqi Technology Co., Ltd.**,
Shenzhen (CN)

(72) Inventor: **Xi Du**, Shenzhen (CN)

(**) Term: **15 Years**

(21) Appl. No.: **29/768,666**

(22) Filed: **Jan. 31, 2021**

(51) LOC (14) Cl. **14-01**

(52) U.S. Cl.
USPC **D14/204**

CLAIM

The ornamental design for a wireless speaker, as shown and
described.

DESCRIPTION

FIG. 1 is a top, front and left side perspective view of a
wireless speaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the
wireless speaker which form no part of the claimed design.

1 Claim, 7 Drawing Sheets
